DESIGN FOR A DICTATING MACHINE OR SIMILAR ARTICLE

Barton A. Proctor, Larchmont, N. Y., assignor to
B. A. Proctor Company, Inc., New York, N. Y., a
corporation of New York

Application December 10, 1941, Serial No. 104,555

Term of patent 14 years

To all whom it may concern:

Be it known that I, Barton A. Proctor, a citizen of the United States and residing in Larchmont, county of Westchester, and State of New York, have invented a new, original, and ornamental Design for a Dictating Machine or Similar Article, of which the following is a specification, reference being had to the accompanying drawings, forming part thereof.

Fig. 1 is a perspective view of the front of the

dictating machine or similar article as viewed from the left showing my new design;

Fig. 2 is a similar view of the front as viewed from the right; and

Fig. 3 is a rear perspective view thereof.

I claim:

The ornamental design for a dictating machine or similar article, as shown.

BARTON A. PROCTOR,
